UNITED STATES PATENT OFFICE.

BERNARD A. STOWE, OF CLEVELAND, OHIO, ASSIGNOR TO THE JANDUS ELECTRIC COMPANY, OF CLEVELAND, OHIO, A CORPORATION OF OHIO.

MEANS FOR PRODUCING AIR-CURRENTS.

No. 816,759.

Specification of Letters Patent.

Patented April 3, 1906.

Application filed June 27, 1903. Serial No. 163,423.

To all whom it may concern:

Be it known that I, BERNARD A. STOWE, a citizen of the United States, and a resident of Cleveland, county of Cuyahoga, and State of Ohio, have invented a new and useful Improvement in Means for Producing Air-Currents, of which the following is a specification, the principle of the invention being herein explained and the best mode in which 5 I have contemplated applying that principle, so as to distinguish it from other inventions.

My invention relates to means for producing air-currents, and particularly to rotatory fans arranged to automatically revolve about 15 an axis, so as to continually change the direction of the air-current produced thereby relatively to a fixed plane.

The object of said invention is to produce means for such described purpose which will 20 allow of a wider range of variation in such change of direction; and the invention consists of means hereinafter fully described, and particularly set forth in the claims.

The annexed drawings and the following 25 description set forth in detail certain mechanism embodying the invention, such disclosed means constituting but one of various mechanical forms in which the principle of the invention may be used.

30 In said annexed drawings, Figure I represents an elevational view of a combination illustrating an air-current-producing structure embodying my invention, showing a portion of the revolving fan support or bracket in vertical axial section. Fig. II represents a plan view of such fan-support, partly in horizontal section, showing also the fans and fan-motors in dotted lines, parts being omitted. Fig. III represents a horizontal sec- 35 tional view of the said revolving bracket, taken upon the planes indicated by lines 3 3, Fig. I, a portion of two oscillatory brake-arms connected therewith being shown in plan. Fig. IV represents a vertical transverse 40 axial section of one of two duplicate motor-frames embodied in my said invention, together with a section of the bracket-arm upon which such motor-frame is mounted. Fig. V represents a side elevation of one of said two 45 duplicate motor-frames, showing a portion thereof in vertical axial section. Figs. VI and VII represent detail views of parts of said structure. Fig. VIII represents a plan view of

said structure, showing the relative position of the axes of the motors and rotatable bracket- 55 support when in one of the normal positions. Figs. IX and X represent diagrammatic views of the scheme of wiring utilized in said combination structure. Fig. XI represents a front elevation of a modified fan structure 60 embodying my said invention, showing the supporting-standard in section. Fig. XII represents a plan view of such modified structure.

Referring to the structure shown in Figs. I 65 and II, a depending supporting-rod A is provided, which will hereinafter be assumed to be fixed in contradistinction to being rotary or revoluble, though it may depend from a cord or chain which will allow a limited 70 amount of oscillation. The lower end of this supporting-rod is threaded and has screwed upon it a sleeve a, whose upper portion is cupped, as shown, and supports a ball-race cup a', holding balls a''. Upon these balls is 75 supported a bracket B, whose upper or guiding portion is formed with a cross-piece b, provided with a central aperture b', countersunk at its lower end to receive a ball-cone b'', which rests upon the balls a'', as shown, the 80 rod A extending through such cone. The upper end of the bracket is formed with a circular bearing which turns upon a journal a'', formed upon a sleeve a', screwed upon the rod A, the latter being provided with suitable 85 threads for such purpose. As illustrated, rod A is made in two sections, the lower end of the upper and the upper end of the lower being screwed into the upper and lower ends of the sleeve a', such construction offering 90 greater facility to the assembling of the parts. A set-screw b'' is provided in the said upper bracket end, which may be caused to bind upon journal a'', and so fix the bracket and rod relatively to each other when required. 95 This set-screw, however, is not ordinarily used and in so far as the invention is concerned forms a superfluous element. The construction of the bracket in other respects is such as to permit it to turn freely upon 100 the balls about the axis of the depending rod A as an axis of rotation. In order to avoid confusion, I shall hereinafter refer to axes intersecting the movable bodies themselves as "axes of rotation" and to axes 105 falling without the bodies themselves as

"axes of revolution." The lower portion of the bracket is provided with two laterally-extending arms B' B', preferably on opposite sides of the rod and having their axes distant 5 from each other one hundred and eighty degrees. These arms and all parts connected therewith are of a length and weight such as to distribute the elements in equal parts upon diametrically opposite sides of the axis of the 10 rod A, and so balance the entire structure to facilitate its rotation, as will be readily understood. Each of these arms includes an oscillatory arm B², Figs. I, II, III, and VI, which is pivoted upon a bolt b⁴, supported 15 upon the portion of the arm integral with or fixed to the bracket, as shown in Fig. IV, each such arm having a plane of oscillation intersecting a plane of rotation of the bracket. The said arms, including the oscillatory 20 members, are preferably made tubular, as shown, to obtain a structure of least possible weight consistent with the required strength. The inner end of each such oscillatory arm B² is provided with an extension 25 b⁵, upon which is secured a wooden brake-shoe B⁵, whose upper surface extends beneath the lower surface of the cup-shaped portion of sleeve a, as shown in Fig. I. This shoe is caused to bear upon such sleeve-surface 30 face with varying degrees of intensity, as will hereinafter be explained. Each oscillatory arm is formed with an upwardly-projecting portion b⁶, formed with a concave recess b⁷ and a groove b⁸, which latter intersects the 35 cavity formed by the hollow arm B². A detached member B³ of a conformation similar to that of the portion b⁶ is provided with a recess b⁹ and groove b¹⁰, similar to those of said portion, the two recesses forming an interior cavity and the two grooves a duct 40 communicating with the interior of arms B'. The extreme upper portion of the member B forms a hollow journal b¹¹, provided with a duct b¹², open at its upper end, the extreme 45 upper end of the journal being threaded, as shown. In the interior of the cavity formed as described are located two shells b¹³ b¹⁴, having opposite interlocking teeth b¹⁵, each shell being held against rotation on its axis 50 by means of lugs b¹⁶ and b¹⁷, respectively projecting into the described upper and lower ducts, as shown. A bolt b¹⁸ passes loosely through member B³ and portion b⁶ and has a plate b¹⁹ secured to one end, the opposite end 55 being threaded and provided with a thumb-nut b²⁰, by means of which the two shells, portion b⁶, and member B³ may be loosened, so as to permit the shells to disengage and the member B³ to turn upon the bolt b¹⁸. By 60 these means the member B³ may be adjusted to assume various upright angular positions relatively to its arm B'. Upon the journal b¹¹ is mounted a motor-frame C, which may be secured in various positions in planes intersecting the plane of adjustment of member 65 B³ by means of a nut c, screwed upon the end of the journal. A suitable electric motor is mounted upon each such frame and inclosed in a suitable casing secured to the latter. The shafts C' of these motors extend outwardly beyond the casings, and upon their ends are respectively secured ordinary fans C². The axes of rotation of these fans—that is, the axes of rotation of the shafts—are preferably caused to lie in a vertical plane 70 passing through the axis of journal b¹¹, and such axis is preferably caused to lie in a vertical plane passing through the axis of rotation of the bracket, as shown in the drawings, although such described relationship may be 80 varied without departing from the spirit of my invention. The principal condition necessary to consider in the construction of the class of these devices which are designed to project a current of air in a horizontal direction or in directions inclined thereto are those required to effect an adjustment of the fan-axis so as to impart to it various positions in a horizontal plane and various positions in a vertical plane or, generally speaking, various 85 positions in two intersecting planes. The construction of the motors is immaterial to the present invention. The wires connecting the positive and negative brushes of each motor are led from the interior of the motor-case, down through the duct b¹², between the two shells b¹³ and b¹⁴, through the duct formed by the grooves b⁸ and b¹⁰, and into the interior of the corresponding arm B', from whence they pass and are connected as hereinafter described. The member B³ of each oscillatory arm is preferably located with reference to the axis of oscillation thereof so 90 that the axis of journal b¹¹ when vertical will intersect the said axis of oscillation, and it will therefore be seen that under such conditions when the members B³ are inclined outwardly the center of gravity of the mass supported by each such member B³ will fall without its axis of oscillation and each oscillatory arm B² will be tilted so as to cause the brake-shoe connected therewith to automatically 95 exert a pressure against the under surface of the sleeve a. Such pressure will be augmented during the rotation of the bracket and connected parts by the centrifugal force of the mass mounted upon the members B³ and will hence be directly proportional to the velocity of rotation. In order to regulate and control such pressure independently of the sole action 100 of the centrifugal force and weight of relevant parts, so as to vary the intensity of the friction for a given amount of rotating force exerted upon the bracket, two springs D D are mounted in barrels b²¹ b²¹, formed in and secured to the bracket, one such spring being located above and exerting pressure upon each oscillatory arm B², so as to oppose the action of the weight of the parts and centrifugal force 105 tending to cause the brake-shoe to press upon 110 the sleeve a. The springs D D are of such 115 construction as to be compressed by the pressure of the rotating mass, and to exert a pressure upon the oscillatory arms B² which is proportional to the velocity of rotation. The barrels b²¹ b²¹ are secured to the bracket by means of bolts and nuts, and are 120 so located as to be in line with the axis of rotation of the bracket. The barrels b²¹ b²¹ are of such 125 construction as to be compressed by the pressure of the rotating mass, and to exert a pressure upon the oscillatory arms B² which is proportional to the velocity of rotation. The barrels b²¹ b²¹ are secured to the bracket by means of bolts and nuts, and are 130 so located as to be in line with the axis of rotation of the bracket.

its braking-surface. By means of a plunger *d* and screw *d'* such counteracting pressure may be varied to suit varying requirements of speed of rotation of the bracket and connected parts. Assuming now that a constant force be applied for rotating the brackets and connected parts, it will be seen that a certain constant speed of rotation may be attained and that, if desired, such speed may be varied by adjusting the screws *d'* without varying the amount of rotatory force. A current of electricity is supplied to the motors, so as to rotate each upon its axis at a substantially constant speed. Such constant rotation will hence produce a substantially constant force acting upon or tending to act upon the parts of the above-described structure with a result depending upon the adjusted relationship of parts, such force being created by the reactionary effects of the volume of air projected by the fan-blades. As illustrated, the fan-blades have an inclination such as to require a direction of rotation indicated by arrows in Figs. II and VIII. It will therefore be seen that the motors and fans may revolve about an axis of revolution which is coincident with the axis of rotation of the bracket. I shall now describe various adjusted relationships of the fan relatively to their axes of revolution and the resultant effect. Throughout the following description I shall assume that the springs *D* are set so as to exert a given pressure and remain undisturbed, so that they will not be taken into consideration.

Let it be assumed that the parts are set so as to cause the fans' axes of rotation to intersect their axis of revolution (the axis of the rod *A*) and that both axes of rotation lie in the same straight line. Under these conditions it will be apparent that a condition of equilibrium will be produced and no rotation of the bracket result. Now let it be assumed that the axes of fan rotation intersect the axis of revolution and that the axes of rotation both incline downwardly from a horizontal plane—that is, do not fall in the same straight line—as shown in Figs. I and II. Let it also be assumed that the entire reactionary force exerted by the arm upon each fan-blade be concentrated at the center of gravity of its outer surface. Referring to but one fan, as indicated by the parallelogram of forces, Fig. II, the resultant reactionary force upon each fan-blade may hence be resolved into two components, one tangent to the circle whose circumference contains the center of gravity and whose center lies in the axis of rotation of the bracket and the other of which is perpendicular thereto and parallel with the axis of rotation of the fan, which I shall term the "radial component." As stated, these components and their relationship are shown in the parallelogram of forces indicated in Fig. II. The radial components exert equal

and opposite effects upon opposite sides of the plane represented by line *X Y* containing the axis of fan rotation and axis of revolution, balance each other, and hence exert on revolutionary effect upon the mechanism. For convenience I shall designate those component forces or resultant forces or moments which revolve or tend to revolve the structure about the axis of rod *A* in the direction of the hands of a clock when viewed in plan "positive" forces and those of opposite action "negative." The tangential components of force acting upon the blades whose center lines lie above the plane *X' Y'*, Fig. I, containing the axis of fan rotation and perpendicular to plane *X Y* tend to rotate the bracket in the direction of the arrow 1, Fig. II, and are hence positive. Those tangential components acting upon blades whose center lines are below such plane tend to produce rotation of the bracket in the opposite direction, as indicated by arrow 2 in said figure, and are hence negative. Such tendency of the force of each blade is directly proportional to the amount of force obtained by multiplying the force by the perpendicular distance of each center of gravity of each outer blade-surface from the axis of revolution of the fans and motors—i. e., the bracket's axis of rotation. The forces upon the different blades being equal to each other, it will hence be seen that the moments will be proportional to the said distances. These distances are obviously greater in the upper fan-blades than in the lower, and hence the moments of force involving the positive will predominate, and the resultant moment will effect the revolution in the direction of the arrow 3, the amount of such moment being equal to the algebraic sum of all the moments acting to effect revolution, the ultimate result, as will be seen, being positive. Assuming the length of the arrow 1 to be proportional to the combined positive moments acting in the direction indicated and which is the resultant direction of revolution and the arrow 2 to be proportional to the combined moments acting in the opposite direction, it will be seen that the positive resultant active moment of force may be represented by an arrow 3 of a length equal to the difference between said arrows 1 and 2. It is equally obvious that the amount of such resultant moment will depend upon the degree of inclination of the axes of rotation. This resultant moment, which produces ultimate revolution, is, however, of small value, since the value of the tangential components varies from zero when the center lines of the blades are in a horizontal plane to a maximum when the said center lines are in a vertical plane. In addition, however, from this comparatively weak moment must be subtracted the resultant moment of force involving the blades whose center lines fall below plane *X' Y'*. It

will therefore be seen that in order to utilize the tangential component for effecting revolution of the structure at a required speed limitations in the construction are involved in so far as pertains to weight of parts and delicacy of mounting upon the bearings. However, these limitations are reduced to a minimum by utilizing the double symmetrical construction illustrated so as to obtain

10 a perfect balance of revolving parts.

As has been previously pointed out, the radial components of reactionary force upon the fan-blades in the above-described arrangement exert no effect in so far as pertains 15 to the rotation of the bracket, and it will be observed that when the axis of rotation of the fan not only intersects the axis of revolution, but is also perpendicular thereto, all the forces and couples resolve themselves 20 into a state of equilibrium and no revolution results. It hence follows that in a construction designed to hang or stand in a perpendicular position, so as to cause the bracket to rotate in horizontal planes, the axes of fan 25 rotation must always be inclined to such plane and the resulting air-current must have an upward or a downward trend. Furthermore, the inclination must be sufficient to produce a resultant moment of force 30 which will overcome the inertia of all the revolving parts. In order to avoid such limitations, I have provided the before-described features of adjustment whereby the motors may be adjusted in a second plane intersecting 35 plane X Y, so as to permit the axis of revolution of the fans and motors to fall without the plane indicated by line X² X³, Fig. VIII, parallel therewith and which contains the axis of fan rotation, and thereby, 40 as will be explained, permits the radial components of the reactionary forces to become operative. Assuming that such adjustment is effected in each fan-shaft and the axes of rotation are inclined downwardly, their 45 vertical planes parallel with each other and do not intersect the axis of revolution, as shown in Fig. VIII, as before, the tangential components act positively and negatively and effect a small resultant positive moment 50 which tends to rotate the bracket in the direction indicated by arrow 8, Fig. VIII, in the manner previously described in connection with Fig. II. The radial components, however, also act and produce a moment 55 equal to the sum of the radial components multiplied by the perpendicular distance from the axis of revolution to the projected line indicating the direction of such radial components, as indicated by lines X² 60 X³ and X³ X⁴, Fig. VIII. These moments vary from a positive minimum to a negative maximum; but a majority of the moments involving the radial components are negative, so that their resultant moment is negative—that is, produces revolution in the di-

rection opposite that of the hands of a clock. The ultimate resultant of both systems tending to produce revolution, however, is negative and is the algebraic sum of the moments involving the tangential as in Fig. II and 70 the moments involving the radial components as in Fig. VIII. These resultants and their amounts are indicated by arrows 4, 5, 6, 7, and 8 in said Fig. VIII. The effect of the moments involving the radial components 75 may be augmented by changing the adjustment in the mechanism to effect a horizontal position of the axes of rotation of the fans, the axial lines in Fig. VIII serving to illustrate such positions. In such case the 80 positive moments involving the tangential components will all be in equilibrium, and no tendency to revolve will emanate from that source. By causing the axis of rotation to fall upon the sides of the axis of revolution 85 opposite those upon which they are shown to fall, as indicated by line W W', the resultant moment involving the radial components may be made positive, and by changing the downward inclination of the axes of rotation 90 to an upward inclination the resultant moment involving the tangential components may be made negative. It will therefore be seen that the adjustment of the axis of rotation may be made such as to effect revolution 95 of varying degrees of velocity in either direction while they are inclined or horizontal. A suitable switch and connections are provided for controlling the flow of current to the motors and lamps.

Upon the lower end portion of rod A are secured two metallic slip-rings a⁵ a⁵, which receive the contact of two brushes or spring-terminals B⁴ B⁴, suitably mounted upon the interior of the bracket. Each such ring is 105 suitably connected, preferably by brazing, with a main for supplying current, and one terminal B⁴ is connected with each of the positive terminals of the two motors and the other with each of the negative terminals 110 thereof. The specific connections used in the combination illuminating and fan fixture illustrated are shown in diagram in Figs. IX and X. A three-terminal switch A' is provided with a rotatable contact-segment a⁶, 115 capable of contacting the three terminals simultaneously or connecting any two. One terminal of the main is connected with one of such switch-terminals, the other with one of said slip-rings. A second terminal is connected with the other slip-ring, and the third is connected with such other slip-ring, as shown, by means of a shunt-circuit containing the lamps in parallel. When the segment is contacting all three terminals, Fig. IX, it 120 will be seen that current is supplied to both lamps and motors. When contacting the two terminals, as shown in dotted lines in said figure, current is supplied to the lamps only, and when contacting as shown in dot- 125 130

ted lines, Fig. X, the motors only are supplied. To turn off the current from both motors and lamps, the position of the segment shown in full lines in said last-named figure is employed. The supporting-rod A is preferably made hollow, so as to permit the main wires to be led down upon its inside to the interior of the bracket, from whence they may be led and connected as required.

10 As previously mentioned, Figs. XI and XII illustrate a modified form of fan employing the above-described main principles of operation, which is designed to be placed upon a desk, column, or table and capable of 15 a change of position. In this form a hollow standard E is provided at its upper portion with a ball-race e, which contains balls e', upon which rests a rotatable cone f. This cone is fixed to a vertical hollow shaft F, to 20 the top of which is secured the motor G and casing therefor. Such securing is effected by means of a universal joint F', by means of which the various adjustments described in connection with the first-described structure 25 are obtained. In this case the axis of revolution of the fan is the axis of the ball-bearing formed by the balls, race, and cone. The lower end of the shaft is provided with a friction-collar f', which is surrounded by a friction-ring e², secured to the standard E. This ring has an internal diameter somewhat greater than the diameter of the collar f'. The centrifugal force of the motor and other parts connected with the upper end of the 30 shaft causes the lower end of the axis to oscillate and to describe a circular path during the revolution of the fan. Such action causes the collar to bear against the ring and effect a braking action proportional to the velocity 35 of revolution in a manner similar to that described in the double construction. Upon the extreme lower shaft end is secured a slipping f², which receives the contact of two 40 spring-terminals, by means of which external wires h and internal wires h', passing through the shaft, may be connected to supply current to the motor.

Other modes of applying the principle of my invention may be employed instead of 50 the one explained, change being made as regards the mechanism herein disclosed, provided the means stated by any one of the following claims or the equivalent of such stated means be employed.

55 I therefore particularly point out and distinctly claim as my invention—

1. The combination of a rotatory fan, a rotatory support therefor, and means arranged to automatically exert a positive frictional 60 braking action upon said support directly proportional to the velocity of revolution.

2. The combination of a rotatory fan, a rotatory support therefor, and means controlled by the centrifugal force of its parts arranged 65 to exert a braking action upon said support.

3. The combination of a rotatory support having two arms angularly related to the support's axis of rotation, a rotatory fan and motor mounted upon each such arm, each of the latter including an oscillatory member, and 70 braking means actuated by said oscillatory member, the oscillation of said latter member being controlled by the centrifugal force of the rotating parts.

4. The combination of a rotatory support, 75 a member pivotally mounted upon such support and having a plane of oscillation intersecting the plane of rotation of such support, a rotatory fan mounted upon such member, and a brake for controlling the rotation of 80 said support and controlled by said pivotally-mounted member.

5. The combination of a rotatory support, 85 a member pivotally mounted upon such support having a plane of oscillation intersecting the plane of rotation of such support, a rotatory fan and motor therefor mounted upon said member, and a brake for controlling the rotation of said support, and controlled by said pivotally-mounted member.

6. The combination of a rotatory support having two arms angularly related to the support's axis of rotation, a rotatory fan mounted upon each such arm and arranged to effect the support's rotation, and means for exerting a braking action upon such rotating support, such means arranged so as to be capable of movement toward and from the axis of rotation of said support.

7. The combination of a rotatable support 100 having two arms angularly related to the support's axis of rotation, each such arm including an oscillatory member, a fan mounted upon each of said latter, means for effecting the support's rotation, and braking means 105 actuated by said oscillatory member, the operation of the latter being controlled by the centrifugal force of the rotating parts.

8. The combination of a rotatable support having two arms angularly related to the support's axis of rotation, each such arm including an oscillatory member, a fan and a motor therefor mounted upon each of said latter and arranged to effect the rotation of said support, and braking means actuated by said 110 oscillatory members, the operation of the latter being controlled by the centrifugal force of the rotating parts.

9. The combination of a rotatable support, 115 a fan mounted thereon and arranged to impart a rotating movement thereto, a fixed friction member and means controlled by the rotating parts bearing upon such friction member.

10. The combination of a rotatable support, 120 a fan mounted thereon and arranged to impart a rotating movement thereto, a fixed friction member and an oscillatory arm mounted upon said support arranged to bear upon said friction member and controlled in 125 130

its operation by the centrifugal force of the rotating parts.

11. The combination of a rotatable member, a rotatory fan mounted thereon and arranged to effect the rotation of said member, braking means for controlling the speed of rotation of the latter, and means for varying the intensity of action of said braking means for a given amount of rotating power exerted by said fan.

12. The combination of a rotatable member, a rotatory fan mounted thereon and arranged to effect the rotation of said member, braking means for controlling the speed of rotation of the latter, and a spring arranged to counteract the said braking action.

13. The combination of a rotatable member, means for effecting the rotation of said member, means for effecting a braking action upon said member, and a spring arranged to counteract said braking action.

14. The combination of a rotatable member, means for effecting a braking action upon said member, a spring arranged to counteract said braking action, and means for varying the intensity of action of such spring.

15. The combination of a rotatable support, means for effecting its rotation, means for effecting a braking action upon said member and controlled by the centrifugal force of the rotating parts, and means for varying the intensity of such braking action for a given amount of power exerted by said rotating means.

16. The combination of a rotatable member, a rotatory fan mounted thereon and arranged to effect its rotation, means for effecting a braking action upon said member controlled by the centrifugal force of the rotating parts, and means for varying the intensity of such action for a given amount of power exerted by said fan.

17. The combination of a rotatable member, a rotatory fan mounted thereon and arranged to effect its rotation, means for effecting a braking action upon said members con-

trolled by the centrifugal force of the rotating parts, and an adjustable spring arranged to counteract such centrifugal force.

18. The combination of a rotatable member, an oscillatory arm upon said member, a rotatory fan mounted upon said arm and arranged to rotate said member, revolving parts arranged to actuate said arm by their centrifugal force, and a spring arranged to counteract such force.

19. The combination of a rotatable member, having two arms angularly related to its axis of rotation, and each provided with an oscillatory arm arranged to be actuated by the centrifugal force of revolving parts, a rotatory fan mounted upon each such oscillatory arm, and a spring for counteracting the centrifugal force acting upon each such oscillatory arm.

20. The combination of a support, a rotatable arm mounted upon said support, a fan-motor mounted upon said arm, electric illuminating means carried by said support, conductors connecting said motor and illuminating means with a common source of current, and a switch in the circuit, said conductors and switch being arranged to cut in or cut out from the circuit either said motor or illuminating means or both.

21. The combination of a depending support, a rotatable bracket mounted upon the lower part of said support, a fan - motor mounted upon said arm, electric illuminating means carried by said support and mounted below said bracket, conductors connecting said motor and illuminating means with a common source of current, and a switch located at the lower end of said support, said conductors and switch being arranged to cut in or cut out from the circuit said motor or illuminating means or both.

Signed by me this 17th day of June, 1903.

BERNARD A. STOWE.
